UNITED STATES PATENT OFFICE.

JOSEPH E. WAINWRIGHT, OF BROOKLYN, NEW YORK.

VALVE-GRINDING TOOL.

1,345,043.

Specification of Letters Patent. Patented June 29, 1920.

Application filed August 9, 1919. Serial No. 316,347.

To all whom it may concern:

Be it known that I, JOSEPH E. WAINWRIGHT, a citizen of the United States, residing at Brooklyn, in the county of Kings 5 and State of New York, have invented certain new and useful Improvements in Valve-Grinding Tools, of which the following is a specification.

This invention relates to valve grinding 10 tools and more particularly to a manually operated implement for grinding valves of internal combustion engines.

The primary object of the invention is to provide a simple and durable tool which may 15 be easily operated for grinding disk valves while they are disposed in automobile engines.

A further object of the invention is to provide a valve grinding tool which may be 20 operated to prevent lost motion; which will dispense with intricate mechanism and thereby reduce friction; which may be held firmly in position while in use, so that the grinding will be steady and uniform 25 so that the valves will be ground evenly and quickly so that they will be air tight.

A further object of this invention is the provision of a device of this character which consists of comparatively few parts and is 30 simple in construction, but durable and well adapted to withstand the rough usage to which devices of this character are ordinarily subjected.

For a full description of the invention and 35 the advantages and merits thereof, reference is to be had to the following description and accompanying drawings, in which:—

Figure 1 is a perspective view of the implement constructed in accordance with my 40 invention,

Fig. 2 is a longitudinal section through the handle of the implement,

Fig. 3 is a transverse section through the driving wheel,

Fig. 4 is a detail section through the valve 45 engaging element, illustrating its application to a valve, of conventional type,

Fig. 5 is a transverse section through the valve engaging element taken at right angles 50 to that shown in Fig. 4,

Fig. 6 is a detail perspective view of one of the valve engaging pins,

Fig. 7 is a longitudinal section through the handle of the actuating bow showing 55 the adjustment means for the bow,

Fig. 8 is a perspective view of one of the coupling members for the bow string,

Fig. 9 is a perspective view of one end of the flexible bow.

Referring to the drawings, wherein is 60 illustrated the preferred form of my invention, in which like characters of reference indicate like or corresponding parts throughout the several views, the spindle 1 may be of any desired length and is provided at one end with the handle 2. This handle as shown to advantage in Fig. 2 65 comprises the hand grip portion 3 which is provided with a longitudinal socket 4 into which a sleeve 5 is fitted. In one end 70 of the socket 4 is mounted a bearing member 6 which is provided with a conical recess 7 to receive the pointed end of the spindle 1. This member 6, therefore, provides a bearing for the pointed end of the 75 spindle so that the latter may freely rotate in the handle. The sleeve or bushing 5 is provided on one end with an enlarged flange forming a collar 8, at the end of the handle, and a transverse set screw 9 is extended 80 through a screw threaded opening in the collar and the end of the set screw is received in an annular groove 10 formed in the spindle so that the spindle will be held 85 in proper position within the handle and at the same time permitted to freely rotate.

Fixed to the spindle, at any desired point, intermediate its ends is a bushing 11 which may be swaged, keyed or otherwise rigidly 90 fixed to the spindle. The pulley or actuating wheel 12 is mounted upon this bushing 11 and the ends of the bushing are flanged as indicated at 13 to maintain the pulley 95 in position. The pulley is provided with the annular groove 14 which receives the operating belt 15. This belt is preferably 100 constructed of strong material, preferably catgut. The bow 16 is constructed of steel wire, preferably music wire, and is bow shaped as shown. One terminal of the bow 105 16 is provided with a loop 17 forming one member of a coupling element whereby the coupling member 18 fixed to one end of the belt 15 may be received in the loop 17 to secure the belt to this end of the bow. The 110 opposite end of the bow is formed with a spiral socket 19. As shown to advantage in Fig. 7, the bow handle 20 is provided with a central longitudinal opening through which a screw threaded rod 21 is extended,

and the same is provided with a nut and washer 22 engageable with one end of the handle 20. The opposite end of the handle is engaged by one end of the socket 19 and 5 a nut 23 on the screw threaded rod 21 engages the other end of the socket. The forward end of the rod 21 projects beyond the nut 23 and its terminal is provided with a loop 24 which receives the coupling member 25 similar to the coupling member 18 whereby the opposite end of the belt 15 may be attached to the adjustable rod 21. It will be understood that the belt may be tightened or loosened by varying the position of the nuts 22 and 23 and the bow 10 may also be properly tensioned by screwing the nut 23 toward the handle 20. The provision of the socket member 19 also gives the desired rigidity to the bow at the point 15 where the strain is greatest without impairing the resiliency of the bow.

The valve engaging member is attached to the lower end of the spindle 1 and comprises a disk 26 having a central opening to 20 receive the lower end of the spindle 1. The under surface of the disk 26 is provided with a central diametrically extending groove 27 and the lower end of the spindle 1 is slotted as indicated at 28 to receive a plate 25 28' which forms a valve engaging member for certain types of valves. The upper edge of the plate is disposed in the groove 27 and passes through the slotted end of the spindle as shown and is held in position by a fastening pin 29 passed transversely through the 30 plate and slotted end of the spindle. In this manner the plate is not only held in position but the disk 26 is held against rotation on the spindle. The disk is also provided with 35 diametrically opposite slots 30, each of which receives a valve engaging pin 31. Each pin 31 comprises a square head 32 adapted to fit in one of the slots 30 and a screw threaded shank 33 for receiving the 40 fastening nut 34 whereby the pin may be held in the desired adjusted position. The screw threaded portion has a reduced extension 35 forming a pin to be received in one of the recesses commonly found in the conventional form of valve as shown in Fig. 4. The members 31 are adjustable toward or 45 away from each other to be received in the openings in the valve member and are reversible so that they may be inverted wherever 50 by the pins or extensions 35 will extend upwardly so that the plate member 28 may be employed for engaging the valve of the type employing a slot in its upper surface.

In use, the handle of the implement will 55 be held in one hand and the handle of the bow will be held in the other hand. The bow will then be moved backwardly and forwardly and this reciprocatory motion will cause the belt to pass around the pulley 12, 60 the belt being provided with the looped por-

tion 36 which makes one turn around the annular groove 14 in the pulley. The oscillatory movement thus imparted to the spindle 1 will be also imparted to the valve engaging member which will cause the valve to be 70 oscillated in the proper manner. As shown in Fig. 4, the usual coil spring A, generally used on valves of this character, will tend to raise the valve from its seat. While the valve is thus raised, downward pressure being removed from the tool, the valve may be turned slightly and while being turned, pressed downwardly so that the valve finds a new seat or new point of contact with its valve seat. This raising and lowering of the 80 valve, without disconnecting the tool is especially advantageous, inasmuch as it permits the emery or other grinding medium, to be more uniformly distributed while the valve is being oscillated, and the tendency of 85 the valve to force the grinding medium out toward the edge of the valve seat is greatly reduced. The spindle may thus be rapidly raised and lowered while the bow is being rapidly reciprocated, thereby producing a 90 grinding motion which is especially desirable when grinding valves of this character.

The foregoing description and accompanying drawings have reference to what might be considered to be the approved or 95 preferred form of my invention. I desire it to be understood that I may make such changes in construction, combination and arrangement of parts, materials, dimensions, et cetera, as may prove expedient and fall 100 within the scope of the appended claims.

Having thus fully described my invention what I claim as new and desire to secure by Letters Patent, is:—

1. A valve grinder comprising an oscillatory spindle having a valve engaging means mounted thereon, a circular driving member secured to the spindle, a flexible bow comprising a handle having a spring wire secured thereto, a belt provided with a 105 loop engaging the said driving member and having its terminals fixed to the spring wire whereby the said means will impart oscillatory movement to the said circular driving member when the bow is reciprocated. 110

2. A valve grinding tool comprising an oscillatory spindle equipped with valve engaging means and provided with a grooved pulley fixed to the spindle, a bow comprising an arcuate spring wire having a loop at one 115 end and a coil spring at the other end, a belt provided with a loop passing around the said pulley and having one terminal fixed to the loop in the end of the bow, a handle for the bow, and adjustable means passing 120 through the handle and through the said coil spring, and secured to one end of said belt, to vary the tension of said belt.

3. A valve grinding tool comprising a spindle having a grooved wheel fixed inter- 130

mediate its ends, an actuating member comprising a spring bow formed of a length of resilient wire having one terminal provided with a coupling member and the other terminal provided with a socket, a flexible belt provided with a loop passing around the said groove in the pulley, one end of the said belt being joined to the said coupling member at one end of the said bow, a handle for the said bow, a longitudinally adjustable rod passing through the said handle and through the said socket and having one end fixed to the adjacent end of the said belt, and means to adjust the said rod in the said handle to vary the tension of the said belt.

4. A valve grinding tool comprising a spindle, a wheel fixed to the spindle intermediate its end and provided with an annu-

lar groove, a bow provided with a handle, a longitudinally adjustable rod mounted in the handle and projecting beyond one end thereof, a flexible bow having one end mounted on the said rod and the opposite end provided with a coupling member, a flexible belt having one end joined to the said adjustable rod and the opposite end joined to the said coupling member on the said bow, the said belt being provided with a loop passing around the said pulley the said adjustable rod being provided with fastening elements whereby the adjustment of the rod may be maintained to hold the said belt under the desired tension.

In testimony whereof I affix my signature.

JOSEPH E. WAINWRIGHT.
